UNITED STATES PATENT OFFICE

2,178,176

AIR CONDITIONER

Albert J. Lamm, Fremont, Nebr.

Application June 8, 1937, Serial No. 147,130

1 Claim. (Cl. 257—121)

This invention relates to air-conditioners designed for the purpose of cooling the interiors of buildings such as schools, churches, stores, etc., and is adapted for use in connection with or 5 independently of air heating systems.

An object of the invention is to provide a simple but very efficient apparatus which can be installed readily and utilizes, as a cooling medium, water contained within a dug well located beneath or in close proximity to the structure to 10 be cooled.

A further object is to provide an air-conditioner free from objectionable mechanisms, the only 15 working part, if any, being a motor propelled air forcing means to insure proper circulation of the air within the structure where the apparatus is located.

Another object is to provide apparatus requiring little if any attention and which can be adjusted readily to maintain either a closed inside 20 circulation of air or to furnish a constant supply of fresh air from without the structure.

With the foregoing and other objects in view which will appear as the description proceeds, 25 the invention consists of certain novel details of construction and combinations of parts herein-after more fully described and pointed out in the claim, it being understood that changes may be made in the construction and arrangement of 30 parts without departing from the spirit of the invention as claimed.

In the accompanying drawings the preferred forms of the invention have been shown.

In said drawings

35 Figure 1 is a vertical section through a building equipped with an air-conditioner embodying the present improvements.

Figure 2 is an enlarged vertical section through the cooling unit of the apparatus.

40 Figure 3 is a section on line 3—3, Figure 2.

Figure 4 is a section on line 4—4, Figure 2.

In Figure 1 there has been shown a building B provided with a hot air furnace F from which extend a suitable number of air ducts D leading to outlets or registers R located at suitable points within the structure whereby, during cold weather, warm air can be supplied to various parts of the structure after being heated in the furnace.

An air supply duct I is provided with inlets 2 and 3, the inlet 2 being located where it can receive fresh air from outside of building B, while inlet 3 opens into the building at any suitable point. A valve 4 is mounted in the duct I so

as to swing about a pivot 5 into position to close either of the inlets 2 and 3.

That end of duct I remote from the inlets opens into a blower casing 6 the outlet 7 of which opens into the furnace F. This blower can 5 be driven by an electric motor or any other suitable means, as will be obvious and, when in operation, will set up a forced movement of air from duct I to the furnace F and thence through the ducts D to the interior of building B. If inlet 2 is closed an inside circulation of air will 10 thus be established. If inlet 3 is closed the blower will operate to draw fresh air into duct I and then deliver it into the building through ducts D.

For the purpose of cooling the air supplied to 15 the interior of the building it is essential that a well 8 be provided beneath or in close proximity to the building, this well being of sufficient depth to maintain a constant supply of cold water W. It is also essential that there be located in the 20 well a submerged cooling unit communicating with duct I through an intake duct 9 and an outflow duct 10. It is also desirable to position a suitable valve, such as a pivoted blade 11 within duct I at a point where it can be shifted 25 to close communication between said duct and the top of duct 10 or to close duct I at a point between the upper ends of the two ducts 9 and 10. The valve has been shown in this latter position in Figure 1 so that air entering duct I from 30 either inlet 2 or 3 cannot flow directly to the blower casing 6 but must flow downwardly within duct 9 to the cooling unit and thence upwardly through duct 10.

The types of cooling units can vary. Each unit 35 can be made of any suitable material, preferably a metal possessing a high degree of thermal conductivity and the size of the unit and its capacity can be varied to meet the requirements.

In Figures 1 to 4 inclusive there has been shown 40 a cooling unit comprising a rectangular casing 12 provided, along its vertical center with a water column 13 made up of superposed connected tubes 14 the tops and bottoms of which are slotted as at 15 so as to maintain communication between 45 the tubes. The ends of the tubes open through the adjacent walls of casing 12 and are preferably closed by means of screens 16 which serve to keep out objectionable foreign substances which might be contained within the well. 50

Additional water columns 17 are located along two opposed walls of casing 12, each being formed by an inner corrugated wall 18 spaced from the corresponding wall of the casing. Each of these side columns opens through those casing walls 55

at the sides of the column and screens 19 are provided for preventing foreign substances from entering these columns 17.

All of the water columns extend to the top 5 of casing 12. The side columns 17 extend to the bottom of the casing but the central column 13 terminates above the bottom and the lower section or tube 14' thereof is extended laterally toward one of the columns 17 so as to form a 10 throat 20. Duct 9 opens into the top of casing 12 between column 13 and one of the columns 17 and all of the columns cooperate with casing 12 to form an air passage 21 extending downwardly within casing 12 from duct 9 and under section 15 14' to throat 20 from which the passage extends upwardly to the outflow duct 10.

It will be obvious that when the cooling unit 20 herein described is completely submerged in the cold water contained within the well 8, air circulating through passage 21 will be cooled quickly by contact with the water-cooled walls of the 25 passage. Thus with valve 11 positioned as shown in Figure 1, the actuation of the blower will cause a forced circulation of air from one of the 30 inlets of duct 1 downwardly into the cooling unit and thence upwardly to the blower after which the cooled air will be distributed throughout the building as before explained. It is to be understood of course that the cooling unit can be made of any dimensions suitable to meet the requirements, it being possible to increase or reduce 35 the number of sections comprising the water columns.

It is to be understood that the cooling units 35 can be supported at any depth within a well but it is essential that they be completely submerged. While the tubes or air passages within the units are preferably arranged for up and down flow of air, it may be desirable under some

conditions to arrange them for flow of air horizontally. For example instead of arranging the 5 passages vertically in a well they could be placed horizontally. Such an arrangement is so obvious that illustration thereof is not deemed essential.

While the air-conditioner has been shown and described as associated with a heating furnace, it obviously could be installed independently thereof, a flue section being substituted for the furnace F.

The number of air outlets communicating with the blower can vary according to the requirements and while several have been shown at 10, it is to be understood that under some conditions the outlet from the blower casing would meet the 15 requirements and no flues would be necessary for distributing air.

In practically all installations of these air-conditioners the ducts 9 and 10 can be used as the 20 sole means for supporting the cooling unit while submerged in the water in the well.

What is claimed is:

An air-conditioner including a casing; spaced 25 upwardly extending water columns extending through and connecting opposed walls of the casing, said columns having corrugated walls constituting the walls of an air passage between the columns, said walls providing superposed convex surfaces exposed in the air passage and extending from one to the other of said opposed 30 walls of the casing, said air passage having an inlet and an outlet at the top of the casing, ducts extending to the inlet and outlet respectively and constituting means for positioning the casing within water contained in a well, thereby to maintain 35 the columns full of water, and means for setting up a forced circulation of air through the ducts and passage and across the convex surfaces.
